UNITED STATES PATENT OFFICE.

WALTER W. PHILLIPS, OF JERSEY CITY, NEW JERSEY.

CARPET-RETAINER.

1,091,862.

Specification of Letters Patent. Patented Mar. 31, 1914.

Application filed March 4, 1912. Serial No. 681,592.

To all whom it may concern:

Be it known that I, WALTER W. PHILLIPS, a citizen of the United States, residing at Jersey City, in the county of Hudson and State of New Jersey, have invented certain new and useful Improvements in Carpet-Retainers, of which the following is a specification.

This invention relates to retainers for carpets for stairways and the object is to provide a device for holding a strip of carpet in proper place on a stairway.

Another object of the invention is to provide a self-retaining means for holding the carpet in place upon a stairway.

Still another object of the invention is to provide a resilient carpet retainer whereby a carpet may be retained to a stairway without use of tacks. And still another object is to provide a resilient carpet retainer whereby said resiliency will hold said retainer to a stairway without use of nails, screws, etc.

With the above and other objects in view which will be more specifically explained in the following specification I have invented the device illustrated in the accompanying drawings, in which,

Figure 1 is a detached front view of my carpet retainer, Fig. 2 is a front elevational view of a portion of a stairway showing my device in use, and Fig. 3 is a side elevation of a portion of a stairway showing my device retaining a strip of carpet.

Likewise reference characters indicate like parts throughout the specification and in the several views in the drawings in which—

1 is a resilient carpet-retaining base member having spring arms 2 and 3 which are adapted to engage the under projecting portion of a tread 4. The arms 2 and 3 are connected to the base member 1 by sinuous springs 5 and 6, which are on a vertical plane with said retainer bent offset from said base 1. The construction of the offsets 6 which merge with the carpet retaining member 1 is such that an S-shaped configuration is provided which inclines forwardly, as clearly shown in Fig. 3, but it will be understood that it is the forward inclination of this offset which distinguishes it from the other sinuous offsets.

In use, the carpet strip 7 is passed under the retainer 1 and brought thereover, so as to project forwardly of the arms 2 and 3, which, when in place, assume a vertical position adjacent the risers 9. The tension of

the spring members is sufficient to hold the retainer in proper position, whereby the carpet is held in place upon the stairway 8. And when the spring arms 2 and 3 are thus held in vertical position, the positions of the carpet adjacent said arms will also remain set in vertical position—a desirable feature because of the economy attained. For this purpose the carpet retaining member 1 will bear against the carpet at a point in advance of the axes of the arms 2 and 3.

Numerous modifications and variations can be made in this device without departing from the spirit of the invention.

What I desire to procure by Letters Patent is:

1. A device of the kind described, comprising a bar positioned upon the tread of one step of the stairs, and provided with integrally formed extensions at the ends arranged to engage the next higher step substantially as shown and described.

2. A device of the kind described, comprising a resilient bar, extending across the width of the carpet at one tread, and thence extended at each end to engage the next higher tread.

3. A device of the kind described, comprising a bar arranged at the juncture of the tread and riser on the front side of the carpet, said bar provided with a resilient arm at each end, extending upwardly and back of the carpet to the under side of the next higher tread.

4. A carpet retainer consisting of a single piece of spring wire having a downwardly curved base, said base being resilient and having vertical arms, said base being offset from the plane of said arms and adapted to seat on said carpet.

5. A carpet retainer comprising a single piece of spring wire, said wire having its free ends bent to form straight portions disposed in a similar direction and a convex cross piece disposed at an incline to and in continuation of said two straight portions, said cross-piece have portions substantially S-shaped and merging with said straight portions.

6. A carpet retainer having a base with arms projecting upwardly from its opposing ends and having blunt terminals, said base being offset from the plane of said arms.

7. A carpet retainer consisting of a member having a downwardly curved base with arms bent inwardly from the ends thereof

and then projecting upwardly to engage a stair tread.

8. A retainer comprising an arcuate base having vertical offset arms with blunt terminals, said base being resilient.

9. A retainer comprising an arcuate base having vertical offset arms with blunt terminals, springs connecting said base to said arms, said base, arms and springs being formed of a single piece of wire.

10. The described device consisting of a

carpet strip retainer having an arcuate base, vertical arms, and an inclined connection between said base and arms, said arms being vertically resilient.

In testimony whereof I affix my signature in presence of two witnesses.

WALTER W. PHILLIPS.
